FONT OF DISPLAY LETTERS

Dean H. Reynolds, Rochester, N.Y., assignor to Eastman Kodak Company, Rochester, N.Y., a corporation of New Jersey

Filed May 9, 1961, Ser. No. 65,089

Term of patent 14 years

(Cl. D64—12)

Fig. 1

Fig.1a

Fig.2

Fig. 2aFig. 3FIGS. 1 and 1a illustrate the upper case of a font of display letters showing my new design;

FIGS. 2 and 2a illustrate the lower case letters thereof; and

FIG. 3 is an enlarged, detailed fragmentary view of one edge portion of one of the letters, same being common to all the letters that are illustrated in solid lines.

The essential features of my design reside in the portions shown in solid lines, the illustration of the letters in broken outline being merely for the purpose of completing the alphabet.

This application is a continuation-in-part of my copending application Serial No. D. 62,565, filed October 21, 1960.

I claim:

The ornamental design for a font of display letters, substantially as shown and described.
